DESIGN FOR AN AIRPLANE

Michel Wibault, New York, N. Y.

Application September 21, 1946, Serial No. 133,494

Term of patent 14 years

(Cl. D71—1)

To all whom it may concern:

Be it known that Michel Wibault, a citizen of the Republic of France, residing at New York, in the county of New York and State of New York, has invented a new, original, and ornamental Design for an Airplane, of which the following is a specification, reference being had to the accompanying drawing, forming part thereof.

Fig. 1 is a front perspective view of an airplane, showing my new design;

Fig. 2 is a rear perspective view thereof;

Fig. 3 is a plan view thereof;

Fig. 4 is a front elevation thereof; and
Fig. 5 is a side elevation thereof.

I claim:

The ornamental design for an airplane, as shown.

MICHEL WIBAULT.
